Patented Sept. 13, 1921.

Fig. 3.

UNITED STATES PATENT OFFICE.

WHITTLESEY A. DRAKE, OF PETROLEUM, OHIO.

TANK-BAND SADDLE.

1,390,511.

Specification of Letters Patent. Patented Sept. 13, 1921.

Application filed June 19, 1920. Serial No. 390,192.

To all whom it may concern:

Be it known that I, WHITTLESEY A. DRAKE, a citizen of the United States, residing at Petroleum, in the county of Trumbull and State of Ohio, have invented certain new and useful Improvements in Tank-Band Saddles, of which the following is a specification, reference being had therein to the accompanying drawing.

10 This invention relates to an improvement in tank band saddles, and is to be used on tanks of tank cars.

It is well-known to those who understand the construction of tank cars, that bands 15 pass over the tanks and have their ends suitably connected to the frame of the car. It is also well-known to those familiar with the construction of tanks for cars, that they are made up of metal plates or sheets having overlapped riveted joints.

In tank cars these bands are drawn tightly over the tanks for the purpose of holding them permanently to the frame of the car, and hence the bands engage the outer 25 surface of the tank with considerable pressure. Where the bands pass over the riveted joints, they engage the rivets and cause undue pressure on the joints, which has been found objectionable for the reason that such 30 even or undue pressure is liable to cause leakage as well as bringing the strain on the band at the pointed riveted heads.

The object of my invention is to construct a saddle which will rest upon the outer 35 surface of the tank at the riveted lapped joints, and receive and support the tank band in such manner as to prevent the pressure or strain of the band coming directly upon the riveted joint, as it does now in 40 tank car constructions.

With these ends in view, I construct a saddle which may be composed of one or two parts and which engage the outer surface of the tank at opposite sides of the 45 riveted joint with sufficient thickness to support the band above the rivet heads of the joint and tapered toward its outer ends, whereby the riveted joint is relieved of the direct pressure caused by the band engaging 50 the heads of the rivets.

Furthermore, to provide for the proper engagement of the saddle at opposite sides of the riveted joint, that side adjacent to the outside lap of the joint has an increased 55 thickness as compared with the thickness of the saddle to the opposite side of the

joint equal to the thickness of the metal of which the tank is made, whereby the inner surface of the saddle has a uniform pressure upon the outer surface of the tank at opposite sides of the riveted joint.

In the accompanying drawings:

Figure 1 is a side elevation showing the preferred one-piece form of tank band saddle, it being shown in position in respect 65 to the lapped riveted joint of the tank, the latter shown in section.

Fig. 2 is a top plan view of Fig. 1.

Fig. 3 is a view similar to Fig. 1, showing the two-piece form of my improved tank 70 band saddle.

Fig. 4 is a top plan view of Fig. 3.

In the accompanying drawings, 1 and 2 are plates or sheets forming the shell of the tank and which have an over-lapped 75 joint 3. This overlapped joint is connected by a suitable number of rivets 4. These rivets in the usual construction are arranged in two parallel rows with the rivets in the rows arranged in alternate positions, 80 as clearly shown in Figs. 2 and 4. These rivets have the usual tapered inner and outer ends, as shown, though, in some constructions, the ends of the rivets are rounded. Whether the heads be pointed or rounded, 85 the outer ends project beyond the outer surface of the tank shell 1 and 2, as will be readily understood. The tank band 5 passes over the shell or tank and its lower ends, not shown, are connected with the frame of 90 the car, not shown, in any suitable manner. It is well understood to those skilled in this art, that the ends of the tank band are adjustably connected so that they may be drawn tightly against the tank. As this 95 adjustable construction forms no part of my present invention it is not shown.

My improvement consists of a saddle. Referring now particularly to Figs. 1 and 2, which show the preferred one-piece form 100 of saddle, this comprises an elongated member 6, which extends transverse the lap joint 3, as shown. The center 7 of this elongated member 6, is sufficiently thick to have its center portion 7 in a plane outside of or 105 beyond the heads of the rivets, 7, and is provided with openings or depressions 8 to receive the outer heads of the rivets 4. From this center 7 the saddle tapers upwardly toward both ends as shown, and the tank band 110 5 passes over and engages the outer face of the saddle, whereby the band is prevented

from engaging the outer heads of the rivets 6, preventing it from bringing direct pressure on the rivets and lap-joint, which in use is liable to cause leakage. The saddle is 5 made thicker at one side of the lap-joint than at the other, as shown at 9 and 10. This difference in thickness is equal to the thickness of the material of which the tank shell is composed, whereby the saddle is 10 caused to engage the tank shell with equal pressure at opposite sides of the lapped joint.

For the purpose of preventing the saddle from moving laterally from under the band, 15 the saddle is provided at its edges with outwardly projecting flanges or projections 11, which are located at opposite edges of the band 5. These flanges or projections will prevent any relative lateral movement of the 20 saddle and the tank band and thus prevent lateral displacement, and the outer heads of the rivets which engage openings or recesses in the center of the saddle prevents it from having any longitudinal movement. This 25 longitudinal movement, however, would be prevented by reason of the outward tapers of the ends of the saddle between the band 5 and the shell, since the band after passing over the saddle engages directly the tank shell 1 and 2, as shown at 12. In this one-piece saddle, it is preferably, though not necessarily, provided at one side of its center with laterally extending portions 13 to 30 extend around and embrace the heads of the rivets at these points, as clearly shown in Fig. 2. For the purpose of saving metal, the saddle may have suitable sized openings 14.

In Figs. 3 and 4, I have shown my saddle 40 made in a two-piece form. In this construction, it comprises the two pieces B and C, which are positioned at opposite sides of the lap-joint 3. The inner end 15 of the piece C is made thicker than the inner end 45 16 of the piece B, and this difference is equal to the thickness of the tank shell 1 and 2. These points 15 and 16 of the two-piece form correspond with the points 9 and 10 of the one-piece form and perform the 50 same function. The inner ends 15 and 16 of the two-piece form are made sufficiently thick to support the tank band 5 above the outer ends of the rivet heads as the one-piece does and prevents the band from engaging 55 the outer heads of the rivets and causing direct pressure on the rivets and the lap-joint, which is objectionable for the reason previously stated. These pieces B and C have projections or flanges 17, at their opposite edges between which the band 5 passes and they serve to prevent relative lateral movement of the band and the parts B and C, and therefore prevent lateral displacement. The two pieces B and C taper out-

wardly from their inner ends to correspond 65 with and for the same purpose that the ends of the one-piece form are similarly tapered and the band directly engages the tank shell beyond the outer end of the two parts B and C.

It will be observed that the one and two piece forms operate in the same manner to support the tank band out of engagement with the outer heads of the rivets and thus prevent direct pressure on the riveted lapped 70 joint.

It will be understood, of course, that in the form shown in Figs. 3 and 4, it takes the two pieces to make the complete saddle, instead of a single piece, as in Figs. 1 and 2. 80

I do not limit myself to the precise construction here shown, as variations and modifications thereof may be made without departing from the spirit and scope of my invention, as defined in the appended claims. 85

Having thus described my invention what I claim and desire to secure by Letters Patent is:—

1. The combination with a tank having a lapped riveted joint, of a saddle engaging 90 the tank at opposite sides of the joint and adapted to receive and support a tank band out of engagement with the riveted joint, the saddle having its outer ends tapered outwardly for the purpose described. 95

2. The combination with a tank having a lapped riveted joint, of a tank band saddle engaging the tank at opposite sides of the joint and having a thickness sufficient to receive and support the band out of engagement with the rivets of the joint, the saddle at that side of the joint adjacent the outside edge of the lapped joint being thicker than at the opposite side of the joint equal to the thickness of the material of which the 105 tank is composed, for the purpose described.

3. The combination with a tank having a riveted lapped joint, of a tank band saddle engaging a tank at opposite sides of the riveted joint, the saddle tapering from its inner portion to its outer ends and having at its edges outwardly extending projections, whereby it is adapted to receive a band between the projections and supported out of contact with the outer heads of the rivets. 100 115

4. The combination with a tank having a lap-joint, of a one-piece tank band saddle having its center portion out of contact with the joint and engaging the outer side of the tank at opposite sides of the joint, the saddle tapered from its center outwardly and adapted to receive and support a band out of contact with the lap-joint. 120

5. The combination with a tank having a riveted lap-joint, of a one-piece tank band saddle comprising an elongated member extending transverse the joint and having a center portion thicker than the projection 125

of the rivet heads, the saddle engaging the tank at opposite sides of the joint and having its ends tapered outwardly, whereby it is adapted to receive and support a band 5 out of contact with the outer rivet heads.

6. The combination with a tank having a joint, of a one piece tank band saddle extending across the joint and of a thickness to

support the band out of contact with the joint, the intermediate portion of the saddle 10 cut away at and out of contact with the joint to prevent engagement therewith.

In testimony whereof I hereunto affix my signature.

WHITTLESEY A. DRAKE.
